UNITED STATES PATENT OFFICE.

SAMUEL BARUCH, OF NEW YORK, N. Y.

COOLER FOR INTERNAL-COMBUSTION-ENGINE RADIATORS.

1,411,900.

Specification of Letters Patent.

Patented Apr. 4, 1922.

Application filed May 6, 1918. Serial No. 232,831.

To all whom it may concern:

Be it known that I, SAMUEL BARUCH, a citizen of the United States, and a resident of New York city, borough of Manhattan, in 5 the county of New York and State of New York, have invented a new and Improved Cooler for Internal-Combustion-Engine Radiators, of which the following is a full, clear, and exact description.

10 My invention has for its object to provide a cheap and efficient cooler for internal combustion engine radiators, the cooler having a drum in which extends a perforated tube connected with the interior of the radiator, 15 so that the steam may pass upwardly and through the perforations in the tube where it will be cooled by the drum and by the air which will flow upwardly in the radiator overflow pipe to the drum, the condensed 20 steam flowing back through the lower perforations in the tube and into the radiator.

Additional objects of the invention will appear in the following specification in which the preferred form of my invention 25 is described.

In the drawings similar reference characters refer to similar parts in all the views, in which—

Figure 1 is a sectional elevation showing 30 my improvement; and

Figure 2 is a sectional plan view on the line 2—2 of Figure 1.

By referring to the drawings, it will be seen that a drum 5 is provided, having a head 35 6 at its bottom, in which there is an opening 7 through which is disposed a tube 8. This tube 8 has perforations or orifices 9 above the head 6 and extending above the top 10 of the drum 5, so that its upper end 11 will 40 be disposed in the seat 12 on the cap or head 13 which closes the upper end of the drum. The cap or head 13 is secured in place at the top of the drum 5 by threads 14 which mesh 45 with threads 15 in the drum. There are orifices 16 in the top and at the sides of the cap or head 13 to permit the escape of vapor.

The lower end of the tube 8 is threaded, so that nuts 17, 18 and 19 may be turned thereon, these nuts 17, 18 and 19 being provided 50 for securing the tube 8 in place relatively to the drum 5 and for securing the

drum 5 in position on top of the radiator cap 20 which has an opening 21 through which the lower portion of the tube 8 is disposed. As indicated in the drawings the nut 17 55 presses against the top of the lower head 6 of the drum; the nut 18 presses against the bottom of the lower head 16 and serves to space the drum 5 from the radiator cap 20; the nut 19 being disposed below the top of 60 the cap 20 so that the nuts 18 and 19 will hold the tube 8 and with it the drum 5, securely in position relatively to the radiator.

It will be understood by referring to the drawings that steam from the radiator will 65 pass up the tube 8 into the drum 5 where it will be condensed because of the cooling effect of the air against the drum 5 as the automobile is in motion and also because of the air which will flow up the radiator overflow pipe 22 to and through the tube 8, the vapor and the air from the radiator overflow pipe 22 passing out of the perforations 9 to the drum 5 in a manner readily understood. When the vapor is condensed the fluid will 75 flow through the lower perforations 9 back to the radiator 23 through the lower perforations 9.

Having thus described my invention, I claim as new and desire to secure by Letters 80 Patent:

1. In a cooler for internal combustion engine radiators, a drum with a head at its bottom provided with an opening, and having another head at its top, there being a 85 seat in the last mentioned head, a perforated tube extending through the opening and having its upper end disposed in the seat, there being an opening at the top of the drum, a radiator cap having an opening through 90 which the lower end of the tube is disposed, the lower end of the tube being threaded and three nuts meshing with the thread on the tube, one disposed above the bottom head of the drum, the second between the drum and 95 the cap, and the third within the cap for holding the tube in position relatively to the drum and for securing the tube to the radiator cap.

2. In a cooler for internal combustion engine radiators, a drum with a head at its bottom and another head at its top, there

being an opening in the first head, a perforated tube extending through the opening, and having a thread disposed at the opening, a radiator cap with an opening through which the threaded portion of the perforated tube extends and three nuts meshing with the thread on the tube, one disposed above

the bottom head of the drum, the second being disposed between the drum and the cap, and the third within the cap for holding ¹⁰ the tube in position relatively to the drum and for securing the tube to the radiator cap.

SAMUEL BARUCH.
